UNITED STATES PATENT OFFICE.

SIMON LAKE, OF MILFORD, CONNECTICUT, ASSIGNOR TO THE LAKE TORPEDO BOAT COMPANY OF MAINE, OF BRIDGEPORT, CONNECTICUT, A CORPORATION OF MAINE.

APPARATUS FOR TRANSPORTING SUBMARINE TORPEDO-BOATS OVERLAND.

1,219,647.

Specification of Letters Patent.

Patented Mar. 20, 1917.

Application filed June 14, 1915. Serial No. 34,040.

To all whom it may concern:

Be it known that I, SIMON LAKE, a citizen of the United States, residing at Milford, in the county of New Haven and State of Connecticut, have invented certain new and useful Improvements in Apparatus for Transporting Submarine Torpedo-Boats Overland, of which the following is a specification.

- 10 The object of the invention is to provide an improved apparatus for the over-land transportation of submarine torpedo boats, whereby to permit the transfer of this class of boats from one port or station to another 15 in considerably less time than would be possible for the boats to proceed by sea under their own power, especially in adverse weather conditions, thus enabling a comparatively small number of submarine torpedo boats to defend a greater number of harbors and a greater extent of coast line, than is now possible with the same number of boats.

It is an acknowledged fact that submarine 25 torpedo boats have proven of the greatest advantage in warfare, and especially in keeping a blockading fleet outside of the limits of the reach of their guns, and in holding a fleet inside of its harbor. It is 30 also well known that owing to weather conditions, submarine boats are unable to travel great distances without seeking shelter, and without replenishing their supplies. These conditions, necessarily consume much valuable 35 time, and oftentimes prevent a boat from reaching the locality, at which an enemy's fleet is reported, in time to intercept the fleet. With my apparatus, this objection is over-come, since by it submarine torpedo 40 boats may be conveniently and rapidly transferred over-land from one station to another in time to apprehend a hostile fleet.

To this end the invention comprises certain details of construction, combinations, 45 and arrangements of parts as will be hereinafter fully described and then claimed.

In the accompanying drawings illustrating the invention, in which the several figures of which like parts are similarly designated throughout the several views, Figure 1 is a diagrammatic plan view illustrating the manner of connecting a marine railway with that of the main line of a railroad. Fig. 2 is a diagrammatic side elevation illustrating 50 a submarine torpedo boat mounted upon my

improved truck and being drawn from the marine railway. Fig. 3 is a diagrammatic side elevation of a submarine torpedo boat mounted upon the truck standing on the main line of the railway. Fig. 4 is a side elevation of the forward end of the truck. Fig. 5 is a transverse section of the same drawn on a larger scale on the irregular line *a-a* of Fig. 3, the cradle being shown in elevation with the central part thereof shown 60 in section. Fig. 6 is a plan view of the forward truck. Fig. 7 is a plan view of the forward truck with the cradle removed.

1 designates a marine railway from which is extended a branch or siding 2 connected 70 with the main line 3 of a railroad through switches (not shown) now in common use. 4 designates my improved carriage comprising trucks 5, which are connected together by suitable truss frames or girders 6, as will 75 be hereinafter again referred to.

Each truck is constructed of side frames 7 of suitable construction having pockets 7' in which are mounted journal boxes 8 of standard design in which are journaled the ends of axles 8 upon which are mounted wheels 9. These parts being of standard construction are shown only diagrammatically. The frames 6 of the trucks are connected by bolsters 10 preferably castings, having hemispherical bearings 11 to receive substantially hemispherical journals 12, formed integral with or connected to transversely arranged cradles 13, the cradles being supported at their ends, upon springs 14, carried by the cradles 13 and having a sliding movement upon the side frames 7, and held in position upon the said frames 7 by lugs 15 cast or formed upon the frames. The springs 14 are connected to the cradles 13, by means of bolts 17 as shown in Fig. 5. The cradles 13 are connected to the truck bolsters 10 by means of king bolts 16, the upper spherical ends of which are socketed in the cradles. Upon the lower ends of these 95 king bolts 16 are arranged springs 18, to allow certain play between the cradles 13 and the truck bolsters 10. The hemispherical bearings 12 are provided with flared outlets 19 for the passage of the king bolts 100 thereby to permit, and to limit, lateral swinging motion of the cradles. By the construction just described, it will be evident that the cradles 13 may move upwardly or 105 downwardly at their ends, and thus com-

110

5 compensate for slight unevennesses in the railroad bed, and hence there will be avoided twisting movement upon the boat when the trucks are rounding curves or meet slightly uneven portions in a roadbed.

10 The cradles 13 are preferably formed with recesses 20 to fit the curvature of the boat to be transported, and the boat is preferably connected to the said cradles 13 by means of tie-rods 21 having their upper ends threaded and inserted through cleats 22 secured upon the side of the boat, and provided with nuts 23, which are threaded upon the bolts above the said cleats. The lower ends of the tie-15 rods engage lugs 24 projecting from the ends of the cradles 13 and said ends are threaded to receive locking and jam nuts 25 as shown. By this arrangement, it will be apparent that a boat may be quickly and securely fastened to the cradles.

20 The bolsters are secured to the side frames by means of bolts 26. However, I desire it understood that I do not limit myself to the employment of bolsters formed of castings, 25 as it will be understood that other constructions may be employed, and which would necessarily necessitate other means than that shown for connecting the said bolsters to the frames 7.

25 As stated, the cradles 13 are connected by suitable truss frames or girders 6, and these frames are preferably constructed of longitudinal angle bars 27, which are suitably bolted to the ends of the cradles and connected together by lattice bars 28, as shown 30 most clearly in Fig. 4. The angle bars 27 are preferably connected to the ends of the cradles 13 by bolts 29, and, in practice, the said angle bars will be made of sufficient length 35 to permit of lengthwise adjustment of the trucks, in order to accommodate boats of different lengths. Tie-bolts 21' will be employed for locking the boat to the angle bars 40 to 27 as shown in Fig. 3.

45 30 designates a submarine torpedo boat of standard construction mounted upon the carriage. In practice, I purpose constructing the boats with removable conning-towers, so as to permit the boats passing 50 through tunnels and under bridges of standard dimensions. I do not claim in this application the details of construction of removable conning-towers, and, therefore, do not consider it necessary to illustrate this 55 feature in detail, and consequently show the conning-tower only in dotted lines.

60 In order to transfer a boat from the water to the land conveyance, a carriage 4 will be run down upon a marine railway so that the boat may be floated thereon, and then securely bolted to the cradles and to the truss frames. The boat may be readily withdrawn from the marine railway on to the siding by means of one or more locomotives 40, as 65 illustrated in Fig. 2. In practice, the car-

riage 4 is connected to the locomotive by means of a cable 41, and after being drawn upon the siding, the cable is detached and the tender of the locomotive is then connected to the forward truck 5 by means of a draw bar (not shown) as will be readily understood.

75 The trucks 5 are connected at their forward and rear ends by transverse bars or connecting plates 42, and the outer bar or plate 42 of each truck is connected to its bolster 10 by means of suitable draw-bar frames 43, between which is mounted the draw-bars 44 of couplers 45.

80 It will thus be seen that I provide an exceedingly simple and efficient apparatus whereby submarine torpedo boats may be quickly and conveniently transported overland from one point to another, thus not only enabling the boats to be quickly transferred and launched from a point distant from its station, but which also avoids the dangers incident to the maneuvering of the boats at sea in adverse weather conditions. It will be understood that when a boat has 90 reached its destination, the carriage is backed down upon the marine railway and the tie-rods removed so that the boat may be floated at high tide or otherwise.

95 While I have shown the several details of my construction in more or less diagrammatic form, I desire it understood that the construction of the trucks may be of other design without departing from the broad principle of the invention.

100 What I claim is:

1. Apparatus for transporting boats overland, comprising wheeled trucks having bolsters provided with bearings, cradles pivotally mounted upon said trucks by means 105 of journals thereon fitted in the bearings on the bolsters and having a laterally loose connection therewith by king bolts thereby to permit a limited lateral swinging motion of the cradles on the trucks, longitudinal frames connected to said cradles, and means to detachably secure a boat to the cradles and frames.

110 2. Apparatus for transporting boats overland, comprising wheeled trucks, bolsters forming parts of said trucks and provided with bearings, cradles pivotally secured to said bolsters and having hollow journals fitted in the bearings and provided with flaring outlets, king-bolts connecting the 115 bearings and journals and permitting limited lateral swinging motion of the cradles on the trucks, longitudinal frames connected to said cradles, and means to secure a boat detachably to the cradles and frames.

120 3. Apparatus for transporting boats overland, comprising wheeled trucks, bolsters forming parts of said trucks and having hemispherical bearings thereon, cradles having hemispherical journals fitted in said 125 130

bearings, king bolts connecting the bearings and journals to permit pivotal movement of the cradles on the trucks, longitudinal frames connected to said cradles, and means 5 to secure a boat to the cradles and frames.

4. Apparatus for transporting boats over-
land, comprising wheeled trucks, bolsters
forming parts of said trucks and having
hemispherical bearings thereon, cradles hav-
ing hemispherical journals fitted in said
bearings, king bolts connecting the bearings
and journals to permit pivotal movement of
the cradles on the trucks, springs interposed
between the trucks and cradles, longitudinal
frames connected to said cradles, and means
to secure a boat to the cradles and frames.

5. Apparatus for transporting boats over-
land, comprising wheeled trucks, cradles
pivotally mounted upon said trucks, longi-
tudinal frames connected to said cradles,
means to change the points of application
of the frames to the cradles so as to lengthen
or shorten the apparatus to conform to the
length of the boat, and means to secure the
boat to the cradles and frames.

6. Apparatus for transporting boats over-
land, comprising wheeled trucks, bolsters
forming parts of said trucks and provided
with bearings, cradles pivotally secured to
said bolsters and having hollow journals
fitted in the bearings and provided with

flaring outlets, king-bolts connecting the
bearings and journals and permitting lim-
ited lateral swinging motion of the cradles
on the trucks, springs interposed between 35
the king-bolts and the bolsters, longitudi-
nal frames connected to said cradles, and
means to secure a boat detachably to the
cradles and frames.

7. Apparatus for transporting boats over-
land, comprising wheeled trucks, bolsters
forming parts of said trucks and provided
with bearings, cradles pivotally secured to
said bolsters and having hollow journals
fitted in the bearings and provided with 40
flaring outlets, king-bolts connecting the
bearings and journals and permitting lim-
ited lateral swinging motion of the cradles
on the trucks, springs interposed between
the king-bolts and the bolsters, springs in-
terposed between the cradles and the trucks,
longitudinal frames connected to said cra-
dles, and means to secure a boat detachably
to the cradles and frames.

In testimony whereof I have hereunto 55
set my hand this 12th day of June, A. D.
1915.

SIMON LAKE.
